15 Claims

ABSTRACT OF THE DISCLOSURE

An apparatus for aligning one elongated member with an elongated reference member. This apparatus has a body which is self-leveling and seats firmly on either the reference member or another member to be aligned therewith, an indicating device on the body for engaging and checking the alignment of the other member, a securing device on the body for securing the body to one of the reference member or the other member and engageable with a hook device on the body.

BACKGROUND OF THE INVENTION

In order to couple together two or more pieces of machinery, it is necessary for the satisfactory operation of such pieces of machinery to correctly align the adjacent shafts of the drive and driven members of the two pieces of machinery. The conventional apparatus for setting and checking the alignment of two such shafts, has an indicating-type instrument or dial indicator graduated in thousandths of an inch mounted on the base or reference shaft and engageable with the shaft to be aligned therewith. One of the conventional mounting means for the dial indicator has included therein the use of magnetic base clamps. Another conventional mounting means comprises a hole drilled and tapped in the reference shaft for the stem of the dial indicator. A still further conventional mounting means required the fabricating of a special clamp and the like. Such conventional mounting means are not always satisfactory and require considerable time to install.

Further, the different shapes and sizes of the various types of couplings increase the problems of aligning the reference shaft and the shaft to be aligned therewith. For example, a mill motor type coupling is secured on a shaft by means of a hexagon nut on the end of the shaft. Again, some couplings are secured on the shafts by bolted plates. In another case some couplings are forced on the shafts with an interference fit. Also the shape of the particular shaft or coupling (i.e. flat, concave, convex or pointed) or the size of the particular shaft or coupling affect the alignment problem.

OBJECTS OF THE INVENTION

It is the general object of this invention to avoid and overcome the foregoing and other difficulties of and objections to prior art practices by the provision of apparatus for aligning one elongated member with an elongated reference member, and an improved mounting means for such apparatus, which apparatus and mounting means:

- (1) are simple and rugged in construction;
- (2) provide substantially maintenance-free operation;
- (3) are quickly and easily mounted on either the reference member or the member to be aligned with the reference member; and
- (4) are adapted for use with all types of shafts and couplings of any size or shape.

2

BRIEF SUMMARY OF THE INVENTION

The aforesaid objects of this invention, and other objects which will become apparent as the description proceeds, are achieved by providing apparatus for checking the alignment of a reference member and another member to be aligned with the reference member. This apparatus has a body provided with a plurality of spaced legs for engagement with one of the reference member and the other member and for self-leveling and for seating firmly the body on the one, indicating means mounted on the body and engageable with the other of the reference member and the other member, hook means on the body, and securing means on the body extending around the one and adapted to engage the hook means to secure the body on the one.

Improved mounting means are provided for mounting the indicating means on the apparatus. The mounting means has a body provided with a plurality of spaced legs for engagement with one of the reference member and the other member, and for self-leveling and for sealing firmly the body on the one, hook means on the body, and securing means on the body extending around the one and adapted to engage the hook means to secure the body on the one.

BRIEF DESCRIPTION OF THE SEVERAL VIEWS OF THE DRAWINGS

For a better understanding of this invention reference should be had to the accompanying drawings, wherein like numerals of reference indicate similar parts throughout the several views and wherein:

FIG. 1 is a side elevational view showing a reference shaft on the left and a shaft to be aligned with the reference shaft on the right, and the apparatus for checking the vertical alignment and horizontal alignment of such shafts and utilizing a side mounting hole in the body of the apparatus;

FIG. 2 is a side elevational view of the body of the apparatus shown in FIG. 1 taken along the line II—II of FIG. 1 in the direction of the arrows;

FIG. 3 is a bottom view of the body of the apparatus with the hook means, tensioning means and the securing means removed for clarity;

FIG. 4 is a fragmentary plan view of a rod-clamping device taken along the lines IV—IV of FIG. 1 in the direction of the arrows;

FIG. 5 is an exploded view of a rod-clamping device; FIG. 6 is a view similar to FIG. 1 showing use of the top mounting hole in the body of the apparatus for checking the alignment of a reference shaft having a smaller diameter than the other shaft;

FIG. 7 is a fragmentary plan view showing use of the front mounting hole in the body of the apparatus for checking the horizontal alignment of a workpiece in a milling machine with a rotary cutter of such milling machine;

FIGS. 8A—8B are bottom views similar to FIG. 3 of alternative embodiments of the legs of the body of the apparatus;

FIGS. 9A—9C are side elevational views of alternative embodiments of the body of the apparatus; and

FIGS. 10A—10E are fragmentary side elevational views similar to FIG. 2 of alternative embodiments of the securing means and hook means.

Although the principles of this invention are broadly applicable to the alignment of an elongated reference member of one machine and another elongated member of another machine, this invention is particularly adapted for use in conjunction with the alignment of shafts, couplings and the like and hence it has been so illustrated and will be so described.

3 DETAILED DESCRIPTION

With specific reference to the form of this invention illustrated in the drawings, and referring particularly to FIGS. 1 and 2, the improved apparatus of this invention for checking the alignment of a reference member (such as a reference shaft 10) and another member (such as the shaft 12 to be aligned with the reference shaft 10) is indicated by the reference numeral 14 (FIG. 1).

This apparatus 14 (FIG. 1) has a body 16 (FIGS. 1-2) provided with a plurality of spaced legs, such as the legs 18a, 18b, 18c (FIGS. 1-3) arranged in a tripod and having flat surfaces 20a, 20b, 20c respectively (FIGS. 2-3) for engagement with flat planar surfaces and inclined surfaces 22a, 22b, 22c respectively (FIGS. 2-3) forming a V-block for engagement with curved surfaces (i.e. concave or convex) or pointed surfaces. The body 16 (FIG. 1) engages one of the reference shaft 10 and the other shaft 12 (in this case the reference shaft 10) for self-leveling the apparatus 14 and for seating the apparatus 14 on the reference shaft 10. A clearance recess 18d (FIGS. 2-3) between the legs 18a, 18b, 18c is adapted to receive pointed surfaces.

In order to hold the body 16 firmly on the reference shaft 10, securing means, such as a timing chain 24 (FIGS. 1-2) is secured to the legs 18b, 18c by a pin 26 (FIGS. 1-2) extending from holes 26a (FIGS. 1-3) in the legs 18b, 18c and between the legs 18b, 18c. The timing chain 24 is wrapped around the reference shaft 10 and is secured in a hook means, such as a hook 28 (FIG. 2). This hook 28 is connected by a link 30 (FIG. 2) to a tensioning means 32 (FIG. 2) for tightening the chain 24 about the reference shaft 10.

TENSIONING MEANS

This tensioning means 32 (FIG. 2) has a rod 32a (FIG. 2) of square cross section connected to the link 30 on one side in this case the left side of the body 16, as viewed in FIG. 2, and passing through a hole 32b' in a round plug 32b (secured as by welding in a countersink 16a of a hole 16b in the body 16) and the hole 16b. The rod 32a has a rounded threaded end 32b (FIGS. 1-2) extending through the other side, in this case the right side as viewed in FIG. 2, of the body 16. The square cross section of the rod 32a and the hole 32b' in the plug 32b prevents rotation of the rod 32a with respect to the body 16 but permits longitudinal reciprocable movement of the rod 32a with respect thereto.

In order to tighten the chain 24 around the reference shaft 10, a knurled nut 32c (FIGS. 1-2) is threadable on the threaded end 32b of the rod 32a and bears against the right side, as viewed in FIG. 2, of the body 16 to move the rod 32a to the right through the plug 32b and the hole 16b, thereby tightening the chain 24 about the reference shaft 10.

For the purpose of adapting the body 16 for substantially universal indicating or checking use, such body 16 is provided with a plurality of threaded mounting holes (FIGS. 1-2) for mounting rods similar to the mounting rod 34a (FIG. 1) of a mounting means 34, such as a top mounting hole 16c (FIGS. 1-2), a through side mounting hole 16d (FIGS. 1-2) to provide mounting on either side of the body 16, and a front mounting hole 16e (FIG. 2).

As viewed in FIG. 1, the side mounting hole 16d is employed to mount a mounting rod 34a for an indicating means, such as indicator dials 36a, 36b for, in this case, checking the vertical and horizontal alignment, respectively, of the shaft 12 with respect to the reference shaft 10.

The structure utilized to mount the indicator dials 36a, 36b (suitably of the type manufactured by the L. S. Starrett Company, Athol, Mass.), and engageable with the other of the reference shaft 10 and the shaft 12, in this case the shaft 12, to check the horizontal alignment

4

of the shaft 12 with the reference shaft 10, is a mounting means 34 (FIG. 1). This mounting means 34 has the indicator dial 36a (FIG. 1) mounted by a screw 34b (FIG. 1) on a rod 34a1, which rod 34a1 is mounted by means of a rod-clamping device 34d (FIGS. 1, 4, 5) on the rod 34a.

For the purpose of mounting the indicator 36b to check the vertical alignment of the shaft 12 with respect to the reference shaft 10, such indicator 36b (FIG. 1) is mounted by means of a screw 34b (FIG. 1) on a rod 34a2 connected by a rod-clamping device 34da (FIG. 1) to a rod 34a3, which rod 34a3 is mounted by a rod-clamping device 34db on the rod 34a.

ROD-CLAMPING DEVICE

This rod-clamping device 34d (FIGS. 1, 4, 5) has a pin 34d1 (FIG. 5) having a rounded end 34d12 provided with a hole 34d13 for the rod 34a1, a straight sided mid portion 34d14 of smaller outside diameter than the rounded end 34d12 and a threaded end portion 34d15 of still smaller outside diameter. A sleeve 34d2 (FIGS. 4-5) is provided with a hole 34d21 (FIG. 5) registerable with the hole 34d13 in the pin 34d1 and a rectangular slot 34d22 (FIG. 5) for receiving the mid portion 34d14 of the pin 34d1 to permit integral rotation of the pin 34d1 and the sleeve 34d2. The pin 34d1 extends through a hole 34d31 (FIG. 5) of a split yoke 34d3 (FIGS. 1, 4, 5) so that the end of the mid portion 34d14 of the pin 34d1 may receive a straight sided hole 34d41 of a washer 34d4 (FIGS. 4-5). A hole 34d32 in the yoke 34d3 receives the rod 34a. A knurled nut 34d5 (FIGS. 1, 4, 5) threads on the threaded end 34d15 of the pin 34d1 to compress a spring 34d6 (FIG. 5) against the washer 34d4, thereby securing the rods 34a, 34a1 in the rod-clamping device 34d.

ALTERNATIVE EMBODIMENTS

40 It will be understood by those skilled in the art that alternatively, as shown in FIG. 6, where a shaft 12⁶ has a larger diameter than a reference shaft 10⁶, a rod 34a4 of the mounting means 34⁶ is mounted in the top mounting hole 16c⁶ of the body 16⁶. The horizontal alignment indicator dial 36a⁶ is mounted by a screw 34b⁶ on a rod 34a1⁶. The rod 34a1⁶ is secured by a rod-clamping device 34d⁶ to a rod 34a⁶, which rod 34a⁶ is connected by rod-clamping device 34dc on the rod 34a4. In turn the vertical indicator 36b⁶ checks the vertical alignment of the shaft 12⁶ with respect to the reference shaft 10⁶ and is mounted as explained with respect to in FIG. 1 on a rod 34a5 in the side mounting hole 16d⁶ of the body 16⁶.

50 In FIG. 7 a milling cutter 38 of a milling machine (not shown) is rotatable in the direction of the arrow on a shaft 40 and is engageable with the work 42 clamped at 43 on a traveling table 44, which table 44 is reciprocable in the direction of the arrows on a bed or frame 46 of the milling machine. Here the apparatus 14⁷ is mounted on the periphery of the cutter 38 and the indicator dial 36b⁷ for checking the alignment of the work 42, is mounted in a front mounting hole 16c⁷ of the body 16⁷. A screw 34b⁷ secures the indicator dial 36b⁷ on the rod 34a8. A rod-clamping device 34dd connects the rod 34a8 to a rod 34a7. A rod-clamping device 34de secures the rod 34a7 to a rod 34a9, which rod 34a9 is connected by a rod-clamping device 34df to a rod 34a7. Such rod 34a7 screws into the front mounting hole 16c⁷ of the body 16⁷.

55 Referring now to FIGS. 8A, 9A, two legs 18a^{8A}, 18b^{8A} are shown having serrated flat surfaces 20a^{8A}, 20b^{8A} for improved gripping on a flat planar surface (not shown) and serrated inclined surfaces 22a^{8A}, 22b^{8A} for improved gripping on curved (concave or convex) or pointed surfaces. The chain 24 (not shown in FIG. 9A) is secured to lugs 26b (FIGS. 8A, 9A) projecting from the leg 75 18b^{8A} by a pin 26 (FIG. 9A) extending through holes

26a in the lugs 26b and between the leg 18b^{8A}. In FIGS. 8B, 9B four legs 18a^{8B}, 18b^{8B}, 18c^{8B}, 18g are provided with flat corrugated gripping surfaces 20a^{8B}, 20b^{8B}, 20c^{8B}, 20g and corrugated inclined gripping surfaces 22a^{8B}, 22b^{8B}, 22c^{8B}, 22g. As shown in FIG. 9C the inclined gripping surfaces 22a^{8C}, 22b^{8C}, 22c^{8C} may be arcuate, either concave (FIG. 9C) or convex (not shown), and have a cross section, such as an irregular curve, parabola, ellipse or hyperbola.

In FIG. 10A the hook 28^{10A} is provided with a resilient retaining member 48 secured to the hook 28^{10A} by a screw 48a. The hook 28^{10A} is provided with a V-shaped end portion 28a. FIG. 10B shows a spring biased clamp 50 connected at 30a to the rod 32a for use with a chain, metal or leather band or an elastic stretchable rope 52. The clamp 50 has serrated or corrugated jaws 50a, 50b and biasing spring 50c. Referring to FIG. 10C, an S-shaped hook 28^{10C} is employed with a metal or leather band 54 provided with holes 54a. In FIG. 10D a buckle 56 having the tongue 56a pivotable at 56b engages a hole 54a^{10D} in a metallic band 54^{10D}. FIG. 10E shows a buckle 56^{10E} pivotable at 56b^{10E} on the link 30 and having bars 57 for use with a flexible plastic or fabric band 54^{10E}.

SUMMARY OF THE ACHIEVEMENT OF THE OBJECTS OF THE INVENTION

It will be recognized by those skilled in the art that the objects of this invention have been achieved by providing apparatus 14 (FIGS. 1-5) etc. for aligning shafts 10, 12 and the like and an improved mounting means 34 for such apparatus 14, which apparatus 14 and mounting means 34 is simple and rugged in construction, provides substantially maintenance-free operation, is quickly and easily mounted on either the reference member 10 or the member 12 to be aligned with the reference member 10, and is adapted for use with all types of shafts and couplings of any size or shape.

While in accordance with the patent statutes preferred and alternative embodiments of this invention have been illustrated and described in detail, it is to be particularly understood that the invention is not limited thereto or thereby.

I claim:

1. Apparatus for checking the alignment of a reference member with another member to be aligned with said reference member, said apparatus having:

(a) a body provided with a plurality of spaced legs for engagement with one of said reference member and said other member and for self-leveling and for seating firmly said body on said one, said body being provided with:

- (1) a side mounting hole for use when said reference member has a diameter substantially the same as the diameter of said other member;
- (2) a top mounting hole for use when said reference member has a diameter substantially different from the diameter of said other member;
- (3) a front mounting hole for use when said reference member is reciprocable with respect to said other member; and
- (4) a tensioning means hole of polygonal cross section;

(b) mounting means in one hole of said side mounting hole, said top mounting hole and said front mounting hole;

(c) indicating means mounted on said mounting means, engageable with the other of said reference member and said other member and for indicating the alignment of said reference member with said other member;

(d) securing means having one end secured to said body and extending around said one,

(e) hook means connected to the free end of said securing means, and

(f) tensioning means connected to said hook means for tightening said securing means about said one;

(1) said tensioning means having a longitudinal member having a polygonal cross section, reciprocable in said tensioning means hole and connected at one end to said hook means and a fastener member threadable on the other end of said longitudinal member and bearing against said body to reciprocate said longitudinal member in said tensioning means hole without twisting said securing means.

2. The apparatus recited in claim 1 wherein said legs have a serrated surface to engage said one.

3. The apparatus recited in claim 1 wherein said legs have a corrugated surface to engage said one.

4. The apparatus recited in claim 1 and having two legs on one side of said body and an opposed leg on the other side of said body.

5. The apparatus recited in claim 1 and having two legs on one side of said body and two opposed legs on the other side of said body.

6. The apparatus recited in claim 1 wherein said hook means is a hook and said hook has a retaining member.

7. The apparatus recited in claim 1 wherein said hook means is a spring-biased clamp.

8. The apparatus recited in claim 1 wherein said hook means is an S-hook.

9. The apparatus recited in claim 1 wherein said hook means is a buckle.

10. The apparatus recited in claim 1 wherein said securing means is an elastic member.

11. The apparatus recited in claim 1 wherein said securing means is a chain.

12. The apparatus recited in claim 1 wherein said securing means is a band provided with a hole.

13. The apparatus recited in claim 1 wherein said securing means is a flexible band.

14. The apparatus recited in claim 1 wherein said hook has a V-shaped end portion.

15. Mounting means for mounting an indicating means for apparatus for checking the alignment of a reference member with another member to be aligned with said reference member, said mounting means having:

(a) a body provided with a plurality of spaced legs for engagement with one of said reference member and said other member and for self-leveling and for seating firmly said body on said one, said body being provided with:

- (1) a side mounting hole for use when said reference member has a diameter substantially the same as the diameter of said other member;
- (2) a top mounting hole for use when said reference member has a diameter substantially different from the diameter of said other member;
- (3) a front mounting hole for use when said reference member is reciprocable with respect to said other member; and
- (4) a tensioning means hole of polygonal cross section;

(b) mounting means in one hole of said side mounting hole, said top mounting hole and said front mounting hole for supporting said indicating means;

(c) securing means having one end secured to said body and extending around said one,

(d) hook means connected to the free end of said securing means, and

(e) tensioning means connected to said hook means for tightening said securing means about said one;

(1) said tensioning means having a longitudinal member having a polygonal cross section, reciprocable in said tensioning means hole and connected at one end to said hook means and a fastener member threadable on the other end of said longitudinal member and bearing against said body to reciprocate said longitudinal member in said tensioning means hole without twisting said securing means.

ber in said tensioning means hole without twisting said securing means.
